RECORD PLAYER TONE ARM OR SIMILAR
ARTICLEDonald F. Kaminski, Du Page County, Ill., assignor to Warwick Electronics Inc., Chicago, Ill., a corporation of Delaware

Filed June 10, 1968, Ser. No. 12,273

Term of patent 14 years

Int. Cl. D14—01

U.S. Cl. D26—14

FIG. 1 is a perspective view of a record changer tone arm or similar article, showing my new design;

FIG. 2 is a side elevational view on a slightly enlarged scale;

FIG. 3 is a top plan view, on the same scale as FIG. 2;

FIG. 4 is a side elevational view taken from the opposite side as FIG. 2, and on the same scale as FIG. 2;

FIG. 5 is an end elevational view, taken from the right-hand end of FIG. 2, and on the same scale as FIG. 2;

FIG. 6 is a perspective view of a modified form of record changer tone arm or similar article; and

FIG. 7 is a fragmentary top plan view, taken along line 7—7 of FIG. 6, and on a slightly enlarged scale.

I claim:

The ornamental design for a record player tone arm or similar article, as shown and described.
